UNITED STATES PATENT OFFICE.

RANDOLPH CROMPTON AND GEORGE CROMPTON, JR., OF WORCESTER, MASSACHUSETTS.

WEFT-REPLENISHING LOOM.

Application filed July 7, 1922. Serial No. 573,357.

To all whom it may concern:

Be it known that we, RANDOLPH CROMPTON and GEORGE CROMPTON, Jr., both of Worcester, in the county of Worcester and 5 Commonwealth of Massachusetts, both citizens of the United States, have invented a new and useful Improvement in a Weft-Replenishing Loom, of which the following, together with the accompanying drawings, 10 is a specification.

Our invention relates to automatic weft replenishing looms, particularly of the type employing shifting shuttle boxes for supplying different kinds of filling.

15 The object of our invention is to provide a loom employing multiple shifting shuttle boxes at each end thereof, and a magazine containing different kinds of filling, from which any shuttle may be automatically replenished with the proper kind of filling.

In so far as we are aware there is no automatic weft replenishing loom on the market at the present time employing multiple shifting shuttle boxes at each end thereof, although 20 automatic looms have been constructed which are provided with multiple shifting shuttle boxes at one end, and with a single shuttle box only, at the other end, where the change of filling takes place. A 25 loom of this general type is shown in U. S. Patent No. 600,053, issued March 1, 1898, to Wyman and Crompton. While a loom constructed in accordance with the above mentioned patent is capable of weaving many 30 classes of fabrics, such as ginghams, colored dress goods, etc., it is not suitable for weaving certain other classes of fabrics such as fancy woolens and worsteds, for the reason that each time a shuttle comes over to the 35 single shuttle box side of the loom it has to return before any other shuttle can be used, thus making it necessary always to use at least two picks of any particular kind or color of filling. When it is desired to 40 weave cloth in which a single pick of any class of filling can be inserted at any time, it is necessary to use what is known as a "pick-and-pick loom," that is, a loom having 45 multiple shuttle boxes at each end of the lay. At the present time however, there is no automatic loom of this type available.

On September 22, 1903, there was issued

to Randolph Crompton, Patent No. 739,651, which disclosed an automatic weft replenishing loom of the pick-and-pick type, in 55 which the shuttles are shown as being operated on their sides, whereby the spent filling carriers are ejected and fresh filling carriers are inserted in a substantially horizontal direction. While the above mentioned 60 Patent No. 739,651 shows an automatic weft replenishing pick-and-pick loom, which appears operative on its face, yet it is a significant fact that there are now no looms of 65 that class running, to the best of our knowledge. It was found by experience that the defect in the mechanism described in Patent No. 739,651 resides in the fact that the shuttle has to run on its side as it travels across the lay, so that the thread has a tendency to catch beneath the shuttle and break.

70 By our present invention we propose to overcome the practical difficulties encountered in building and operating a loom in accordance with the disclosure of Patent No. 739,651, and to this end we have provided a loom employing shifting shuttle boxes at each end thereof, and means for automatically ejecting and inserting filling carriers 75 in a shuttle in one of the boxes, in a vertical 80 plane, whereby the shuttle may run in the normal manner. By our invention therefore, we propose to provide a loom which is both automatic and universal, in that it is weft replenishing and is adapted to weave 85 any class of goods whatsoever. Our invention further contemplates a loom employing a magazine provided with compartments for a number of kinds of filling equal to the maximum number of shuttles that can be 90 employed in both sets of shuttle boxes. The above, and other advantageous features of our invention will hereinafter more fully appear, reference being had to the accompanying drawings, in which,—

95 Figure 1 is a view in front elevation of a loom embodying our invention.

Fig. 2 is a view in end elevation, looking at the battery side of the loom.

Fig. 3 is a view showing a portion of the 100 parts of Fig. 1, on an enlarged scale.

Fig. 4 is a view showing a portion of the parts of Fig. 2, on an enlarged scale.

Fig. 5 is a fragmentary view of a portion

2
of the magazine mechanism shown in Fig. 3, removed from the loom.

Fig. 6 is a fragmentary view showing a portion of the horizontal box mechanism.

5 Fig. 7 is a fragmentary view showing one of the actuating devices appearing in Fig. 1, on an enlarged scale.

Fig. 8 is an end view of the parts shown in Fig. 7.

10 Fig. 9 is a view of one of the actuating cams removed from the loom.

Fig. 10 is a plan view of the shuttle boxes at the magazine end of the loom, on an enlarged scale.

15 Fig. 11 is a side view of the parts shown in Fig. 10.

Fig. 12 is a fragmentary view showing the protective mechanism for the shuttle boxes.

20 Fig. 13 is a diagrammatic view illustrating the various functions of the starting rod.

Fig. 14 is a diagrammatic view illustrating the operation of the loom.

Like reference characters refer to like parts in the different figures.

25 Referring to Figs. 1 and 2, the loom generally comprises a frame 1 upon which is pivotally supported a lay 2 by means of lay swords 3. A plurality of shuttle boxes 4 are mounted at the left hand end of the lay 2, and are adapted to be moved vertically in unison by means of a box rod 5. The boxes 4 are adapted to be raised and lowered in response to a suitable pattern, by mechanism shown in Patent No. 837,284, to which further reference will be made. A picker stick 6 is pivotally mounted on the lay 2 for co-operation with the boxes 4 and is adapted to be driven in unison with a picker stick 7 mounted at the right hand end of the lay by means of an operating mechanism, best shown in Patent No. 340,823, which will be hereinafter referred to.

45 A plurality of shuttle boxes 8, preferably formed in one piece, are carried at the right hand end of the lay 2 and are adapted to be shifted in a substantially horizontal plane. As best shown in Fig. 6, the shuttle box casting 9 is provided with lugs 10 and 11 on opposite sides thereof, to which are secured 50 flexible connections 12 and 13 which extend downwardly over pulleys 12^a and 13^a and are connected to the shuttle box operating mechanism which is shown in the above mentioned Patent No. 837,284, and will be hereinafter referred to. As best shown in Figs. 55 10 and 11, the shuttle box casting 9 is adapted to move back and forth on guide members 14 and 15, carried by the lay 2, the guide member 15 being supported by a bifurcated bracket 16, between the arms of which the picker stick 7 is adapted to move. The guide members 14 and 15 are provided with grooves 14^a and 15^a, respectively, within which are received tongues 17 and 18 provided on opposite sides of the shuttle

box casting 9, whereby the casting is slidably supported for movement in a substantially horizontal plane.

As best shown in Fig. 4, a magazine 19 consists of a plurality of cells 20 arranged vertically in side-by-side relation, the number of cells being determined by the maximum number of shuttles which can be handled by the loom. For purposes of illustration the cells 20 are here shown as being seven in number, seven being the maximum number of shuttles which it is possible to employ when operating the loom with four shifting shuttle boxes at each end thereof, for obviously, one of the shuttle boxes 8 must be kept open to receive an active shuttle. For this reason, the maximum number of cells 20 which are permissible in the magazine 19, is always one less than the total number of shifting shuttle boxes.

85 The magazine 19 is similar in general construction to the magazine shown and described in Patent No. 941,179, and each cell 20 is provided at its lower end with a device to be hereinafter described, for supporting 90 the filling carriers or bobbins 21 therein until a carrier having the proper kind of filling thereon is released for insertion into the shuttle by a transferer 22. The movement of the transferer 22 is adapted to be controlled 95 by the filling feeler mechanism of the loom through a suitable starting rod 23 extending across the loom in back of the breast beam 24, as best shown in Fig. 1.

100 The filling feeler mechanism which we choose to employ forms no part of our present invention, but is fully shown and described in Patent No. 876,418. For this reason it is not believed necessary to show the details of the filling feeler mechanism herein, and for the sake of clearness we have shown only the operating member or starting rod 23 which is adapted to have imparted thereto a longitudinal movement upon the detection of substantial exhaustion of the 110 filling in a shuttle which is about to be driven across the loom from one of the boxes 4, by means of the picker stick 6. It is obvious that other suitable filling feeler mechanisms can be employed in the same manner as that disclosed in the above mentioned Patent No. 876,418, for the purpose of imparting movement to the starting rod 23, for our invention contemplates the utilization of the movement of the starting rod 23 to accomplish a number of different operations which will be described in the order of their occurrence.

115 As best shown in Figs. 1, 3 and 5, a shaft 25 is rotatably mounted on the frame 1 with an arm 26 extending in the direction of the magazine 19. A plurality of lifting levers 27, corresponding in number to the number of cells 20, in the magazine 19, are each pivotally mounted on a rod 28 adapted for 125 vertical movement in guides 29. Each lever 130

27 terminates in a spear shaped head 30, the weight of which tends to overbalance the lever 27 and normally maintain it in engagement with a stop arm 31 at a slight angle from the vertical. Each arm 31 forms a portion of a bell crank lever mounted on a shaft 32, the other arm 33 of which is provided with a curved portion 34 resting on rollers 35 of a pattern chain 36. The pattern chain 36 is driven from a shaft 37 extending across the end of the loom, the chain 36 being so related to the box motion of the loom that the arms 33, each of which corresponds to a given cell 20, will be operated in accordance with the kind of filling which is in the active shuttle, as will hereinafter more fully appear. Each rod 28 is connected through a crank arm 38 to a shaft 39, which extends to one of the cells 20 of the magazine 19. A two armed lever 40 is mounted on the shaft 39 and is provided at its respective ends with stop pins 41 and 42 which extend into the magazine. In their normal position the lower stop pin 42 is disposed beneath the lowermost bobbin 21 of its particular compartment, while the upper stop pin 41 is in position to be moved under the bobbin immediately above the lowermost bobbin, as best shown in Fig. 4. The particular construction of the devices for controlling movement of the bobbins in the magazine forms no part of the present invention, and is more fully shown and described in the above mentioned Patent No. 941,179. Suffice it to say that in the present mechanism shown, the stop pins 41 and 42 are so arranged that an upward movement of any one of the rods 28 will cause a turning movement of the shaft 39, and thereby cause the lower stop pin 42 to release the lowermost bobbin in the corresponding compartment while the upper stop pin 41 will hold the bobbin next above until the lower stop pin 42 has returned to its normal position upon downward movement of the rod 28.

The movement of the pattern chain 36 is adapted to selectively lower the arms 33 in accordance with the arrangement of the rollers 35, and thereby cause the corresponding stop arms 31 to engage the levers 27 and move them in the direction of the arm 26 on the shaft 25, as indicated in dotted lines, Fig. 5. When so moved, any particular lever 27, together with its rod 28, is in position to be raised by the arm 26 upon turning movement of the shaft 25. The shaft 25 is adapted to be turned through shafting 43 and bevel gearing 44 from an operating shaft 45, which is adapted to have rotative movement imparted thereto upon movement of the starting rod 23, by means of an actuating device, best shown in Figs. 7 and 8.

65 The shaft 45 is rotatably mounted on a bracket 46 and an arm 47, adapted to turn therewith, has pivotally mounted thereon a tripping member 48. The member 48 is provided with a weighted portion 49, eccentric about its pivot pin 50, whereby the member 48 normally rests against the end of a plunger 51 in a slightly inclined position. The plunger 51 is slidably supported in a bearing 52 carried by the bracket 46, and is connected at its end to a flexible member 53 passing around pulleys 53^a, to a lug 54 extending downwardly from the starting rod 23, see Fig. 1. In the normal position of the starting rod 23, that is, between the times that the rod is moved upon detection of filling absence, the flexible member 53 tends to hold the plunger 51 in a retracted position against the action of a spring 55, surrounding the plunger 51 between the bearing 52 and a collar 56. Consequently the member 48 remains in position against the plunger 51 so long as the starting rod 23 is not actuated.

As best shown in Fig. 8, a rocker arm 57, pivotally mounted at 58, is provided with an upwardly extending projection 59 carrying a roller 60 which runs in a groove 61, provided on a cam 62, carried on the bottom shaft 63 of the loom. The other end of the arm 57 is provided with a reduced portion 64 having a knife edge 65 extending substantially parallel to a groove 66 provided on the member 48 below the weighted portion 49. Rotation of the bottom shaft 63 is adapted to impart an oscillatory movement to the rocker arm 57, so that the knife edge 65 moves up and down in a substantially vertical plane, just out of engagement with the tripping member 48. The parts remain in the position shown so long as the flexible member 53 holds the plunger 51 retracted, but upon the detection of filling absence and the resulting movement of the starting rod 23, the plunger 51 is released and the spring 55 causes the plunger 51 to move to the right and turn the member 48 in a clockwise direction about its pivot pin 50. As the member 48 falls forward, the knife edge 65 engages in the groove 66 and raises the member 48 together with the arm 47, thereby turning the shaft 45, and with it the shaft 25. Upon this turning movement of the shaft 25 the arm 26 engages the spear head 30 of whichever lever 27 happens to be in its line of movement at that particular time, due to the movement of the corresponding arm 33 by pattern chain. Upward movement of the corresponding rod 28 causes its shaft 39 to be turned, thereby moving the stop pins 41 and 42 and releasing the lowermost bobbin in the cell 20 containing bobbins provided with filling of the same kind that is in the active shuttle. In other words, movement of the starting rod 23, upon detection of any filling absence, is

adapted to immediately release a bobbin having filling corresponding to the kind of filling in the exhausted shuttle that is next driven across to the right hand side of the loom following detection of filling absence. The bobbin is then in position to be acted upon by the transfferer 22, as will be herein-after described.

As best shown in Figs. 1 and 3, the shaft 37 which drives the pattern chain 36, extends across the end of the loom, and is provided with a ratchet wheel 67, the teeth of which are adapted to be engaged by a pawl member 68. The pawl member 68 is pivotally mounted at one end of a bell crank lever 69 mounted at 70, the other end of the lever 69 being connected by a rod 71 to a crank pin 72 carried on a gear 73 driven from the crank shaft 74 of the loom, through a gear 75, see Fig. 2. The turning of the gear 73 is adapted to impart an oscillatory movement to the bell crank 69, which in turn is adapted to impart a step-by-step rotative movement to the shaft 37 by the engagement of the pawl member 68 with the teeth of the ratchet wheel 67. The pawl member 68 is connected by means of a flexible member 76 passing over pulleys 77 to a lug 78 on the starting rod 23, so that when the latter is moved, following the detection of filling absence, the pawl member 68 will be lifted out of engagement with the teeth of the ratchet wheel 67, and thereby arrest movement of the pattern chain shaft 37. The flexible member 76 is so connected to the starting rod 23, that the interruption in the turning of the pattern chain shaft 37 occurs upon the dropping of a filling carrier in the magazine 19, as previously described, so that a new shed cannot be formed, nor can the shuttle boxes be shifted, following the dropping of a filling carrier into position for transfeal to a shuttle. It will be noted that the pattern chain shaft above referred to, carries the usual harness and box motion chain in addition to the magazine chain 36 which indicates for the proper magazine compartment.

Again referring to Figs. 1, 3 and 4, the starting rod 23 is supported at its right hand end in a bearing 23^a, through which it extends, with its projecting end in alignment with an opening 79 provided in a sleeve 80 carried on a rod 81, which has a vertically reciprocatory movement imparted thereto at intervals by means, not shown herein, but fully shown and described in United States Letters Patent No. 805,109. The sleeve 80 extends upwardly and is connected to a pivotally mounted arm 82 by means of a pin 83 working in a slot 84. The arm 82 extends downwardly and is pivotally connected to a lever 85 by means of a pin 86 acting in a slot 87. The lever 85 is provided with a projection 88, which

is in engagement with a downwardly extending portion 89^a of a latch member 89 pivotally mounted on the transfferer 22 by means of a pin 90. The latch member 89 tends to be maintained in a substantially horizontal position by means of a spring 91, so that it is in the path of movement of a bunter 92 carried by the lay 2. The latch 89 however, is adapted to be withdrawn from the path of movement of the bunter 92 each time that the rod 81 is moved downwardly, the lever 85 serving to turn the latch 89 in a clockwise direction about its pivot pin 90. This occurs each time that the lay 2 moves forward during the operation of the loom, but when the starting rod 23 is moved to the right, following the detection of filling absence, the projecting end of the rod enters the opening 79 in the sleeve 80 and thereby prevents downward movement of the sleeve. Consequently the latch 89 is not turned and remains in the position shown in Fig. 4, so that, on the next forward movement of the lay 2, the bunter 92 engages the latch and turns the transfferer 22 about its pivot pin 93. This movement of the transfferer 22 causes it to engage the bobbin which has been previously dropped by operation of the magazine mechanism, as previously set forth, and a fresh bobbin, with the proper kind of filling thereon is inserted into the proper shuttle box. While the latch 89 is adapted to be locked upon the first movement of the starting rod 23, the operation of the transfferer 22 does not occur until the next forward movement of the lay, after the box and harness motions have been thrown off, as previously described. The movement of the starting rod 23 is also adapted to interrupt the operation of the picking mechanism following the arrival of a shuttle with an exhausted bobbin at the right hand side of the loom and the transfer of a fresh shuttle thereto, as will now be described.

As shown in Fig. 1, the starting rod 23 is also provided with a lug 94 which is connected, by means of a flexible member 95 passing around pulleys 96, to the plunger 97 of a second actuating device similar in construction to the actuating device for the bobbin dropping mechanism. The flexible member 95 is so connected to the starting rod 23 that in the normal position of the latter, that is, except when it is moved upon the detection of filling absence, the plunger 97 is held retracted against the action of a spring 97^a. A shaft 98 is also mounted on the bracket carrying the plunger 97, and is adapted to control the mechanism for operating the picker sticks 6 and 7, which mechanism is fully shown and described in the above mentioned Patent No. 340,823. As best shown in Fig. 13, the

shaft 98 is connected to a shipper rod 99 of this mechanism, so that turning of the shaft 98 in a counter clockwise direction is adapted to shift the rod 99 and thereby interrupt the movement of the picker sticks 6 and 7, all as fully shown and described in the above mentioned patent.

An arm 100 is mounted on the shaft 98 to turn therewith, and has pivotally mounted thereon a tripping member 101, which normally rests against the end of the plunger 97 in a slightly inclined position. A rocker arm 102 carries a roller, which travels in the groove 103^a of a cam 103 mounted on the bottom shaft 63 of the loom, and formed as shown in Fig. 9. The end of the arm 102 is provided with a bevelled knife edge 102^a. The parts remain in the position shown so long as the flexible member 95 holds the plunger 97 retracted, but upon the detection of filling absence, and the resulting movement of the starting rod 23, the plunger 97 is released and the spring 97^a causes the plunger to move to the right and turn the member 101 in a clockwise direction. As the member 101 falls forward, the knife edge 102^a engages and raises the member 101 together with the arm 100, thereby turning the shaft 98 in a counter clockwise direction, and interrupting the operation of the picker stick actuating mechanism. Upon the downward movement of the knife edge 102^a the member 101 is released and returns to its normal position by reason of its unbalanced weight, and the picker operating mechanism is resumed by the turning of the shaft 98 in a clockwise direction.

A flexible connection 104 is attached to the shaft 98 and runs over pulleys to a pawl 105 which, as best shown in Fig. 2, controls the rotative movement of the take-up roll 106. Turning of the shaft 98 in a counter clockwise direction, as described above, causes the pawl 105 to be lifted, and thereby interrupt the movement of the take-up roll 106.

The mechanism for operating the respective sets of boxes 4 and 8 is, as previously stated, best shown in Patent No. 837,284, but in order to make clear the relation of the above mentioned patented mechanism to the present invention, reference will be had to Figs. 1 and 2, in which certain essential parts of the box motion are shown. Referring first to Fig. 1, the box rod 5 is received in a sleeve 5^a to which is attached a flexible connection 107, and a second flexible connection 108 is connected to the sleeve 5^a through levers 109. The connections 107 and 108 pass around pulleys 110 and across the loom to an equalizing lever 111. The lever 111 is adapted to have imparted thereto an oscillatory movement through a mechanism which is fully shown and de-

scribed in the above mentioned Patent No. 837,284, and the connections 107 and 108 are connected to the upper and lower ends, respectively, of the lever 111, so that when the lever is operated under the control of the pattern chain, the connection 107 is adapted to raise the box rod 5, while the connection 108 is adapted to lower it, the box motion being entirely positive in its action, as set forth in the above mentioned patent.

The connection 12, which is attached to the lug 10 on the horizontal shuttle box casting 9, is connected to the lower end of a second equalizing lever 112 through a cross lever 113, while the flexible connection 13, which is attached to the lug 11 of the horizontal shuttle box casting 9, is connected to the upper end of the lever 112. The motion of the second lever 112 being similar to that of the first lever 111, it is obvious that the flexible connections 12 and 13 are adapted to shift the horizontal shuttle boxes 8 in opposite directions under the control of the pattern chain. This pattern chain is mounted on the shaft 37, so that when the pawl 68 is raised to interrupt the rotation of the shaft 37, the box motion will be arrested, as previously described.

In order to insure that the shuttle boxes 8 will always properly line up with the shuttle raceway, after being shifted, as just described, we have provided an automatic alining mechanism, best shown in Figs. 10 and 11. The bottom of the shuttle box casting 9 is provided with a plurality of downwardly extending lugs 114 which are on the back walls of the several shuttle boxes 8. A rod 115 is slidably mounted in bearings 116 on the back side of the lay, and is provided at its end with an alining member 117 which extends upwardly in the direction of the shuttle box casting 9. The member 117 is provided with a pair of prongs 118 which are bevelled in the direction of the lugs 114, so that they are spaced apart at their ends by a distance somewhat greater than the thickness of a lug 114. Except at their ends, the distance between them is substantially equal to the thickness of a lug 114. A shifting arm 119, pivotally mounted on the lay at 120, is provided at its upper end with a forked portion 121 which embraces a pin 122 projecting from the rod 115. The lower end of the arm 119 is reduced, as indicated at 123, and is received in a slot 124 provided in an arm 125 projecting from the breast beam 24.

As the lay moves back and forth, the arm 119 has imparted thereto an oscillatory movement by reason of its connection to the arm 125, which movement is translated into a reciprocatory movement of the rod 115. The movement of the rod 115 is so timed that the alining member 117 moves to its right hand position just after the time for

movement of the boxes, and just before the time for picking of a shuttle. Conversely the alining member moves to the left just after the time for receiving a shuttle, and just before movement of the boxes is to commence. In this way the shuttle boxes 8 are brought into exact alinement for reception or rejection of a shuttle.

The outer guide member 15 is provided with a pair of hinge lugs 126, between which is pivotally mounted a U-shaped binder 127 having a slot 128. A spring 129 bears upon the free end of the binder 127 to give the necessary binding action on the shuttles as they enter and leave the boxes. It will be noted that the binder 127 is hinged to the bracket member 15 and does not move sidewise with the shuttle boxes 8. The particular form of the binder 127 forms no part of the present invention, but is fully set forth and described in Patent No. 739,651 to Randolph Crompton.

As best shown in Fig. 12, a diagrammatic view, a protector finger 130 is adapted to cooperate with an extension 131 provided on the binder 127, so that when a shuttle is driven home in one of the boxes 8, the movement of the binder 127 will cause the finger 130 to be turned in a counter clockwise direction and thereby move a dagger 132 downward into the position shown in dotted lines. In case a shuttle is not received in one of the boxes 8 the dagger 132 remains in the full line position, and on the next forward beat of the lay, operates to "knock off" the loom.

In order to make clear the sequence of operation of the several mechanisms previously described, and their relation to each other in the operation of the loom, there is shown in Fig. 13 a diagrammatic view of the starting rod 23 removed from the loom, with the several flexible members 53, 76 and 95 attached thereto and leading to the devices which they are adapted to respectively actuate. With the general view of a loom shown in Fig. 1, and the diagrammatic view of Fig. 13 in mind, it is believed that the operation of the loom will be readily understood therefrom and will now be described.

Let it be first assumed that the loom is operating with a number of shuttles equal to the total number of vertical and horizontal shuttle boxes, less one, and that the magazine is provided with filling carriers having a number of different kinds of filling therein corresponding to the number of different kinds of filling carried in the shuttles. As the loom operates, the filling feeler mechanism cooperating with the vertical set of shuttle boxes 4, functions in the same manner as described in Patent No. 876,418, previously referred to. Inasmuch as the operation of this feeler mechanism is

fully set forth in the above mentioned patent, it is not believed necessary to burden the present application with a detailed description of this operation. Suffice it to say, for the purpose of the present invention, the filling feeler mechanism will not operate to shift the starting rod 23 until a shuttle in which the filling is practically exhausted is ready to be picked to the right hand side of the loom on the backward movement of the lay.

Upon the movement of the starting rod 23, following the detection of filling absence, as described above, let it be borne in mind that a shuttle with a substantially exhausted filling is simultaneously moving from the left hand to the right hand side of the loom. Consequently, when the shuttle arrives in one of the horizontal boxes 8, the movement of the starting rod 23 has already locked the sleeve 80 of the transfer mechanism in position, so that the latch 89 will be tripped and the transerrer 22 operated on the next forward beat of the lay. Before the transerrer 22 is operated however, the movement of the starting rod 23 has released the flexible member 53 and allowed the plunger 51 to set in motion the actuating device which imparts rotative movement to the shaft 45. This rotative movement is in turn transmitted to the shaft 25, thereby causing a bobbin to be dropped from the cell 20 containing bobbins, of the same kind as that which is contained in the detected shuttle just received in the horizontal shuttle boxes 8. The movement of the starting rod 23 also serves to exert a pull on the flexible member 76, thereby lifting the pawl 68 and throwing off the box and harness motion.

It may be here stated that the motion of the bell crank lever 69 is so timed that it is not adapted to move the pattern chain until after the time that the starting rod is adapted to be moved, in other words, the pattern chain is only moved when a shuttle is running and the boxes and harnesses are stationary, which arrangement is most desirable in this type of loom.

Following this occurrence, the bunter 92 on the lay engages the latch 89, thereby operating the transerrer 22 and causing the fresh bobbin which has just been dropped in the magazine, to be transferred to the exhausted shuttle. At this point the pick is thrown off by the turning of the shaft 98 through the actuating device which is set in operation by the release of the plunger 97 by the flexible member 95. The throwing off of the pick prevents the exhausted shuttle, which has just been received in the right hand shuttle box, from being returned to the left hand side of the loom on the pick following, so that there is thus afforded a time interval in which the box and harness

motions may again be resumed by the release of the pawl 68 upon the return movement of the starting rod 23 to its normal position. The picking will then be resumed by the return of the member 101 to its normal position, and the corresponding clockwise movement of the shaft 98. The loom then resumes normal operation until the feeler mechanism again detects filling exhaustion, whereupon the cycle of operations, as described above, will be repeated. The throwing off of the pick occurs just one revolution of the crank shaft after the starting rod has been moved. This is accomplished by timing the movement of the knife 102^a so that it is at the top of its throw upon the movement of the starting rod and moves down quickly right after the picking balls have ceased engagement with the shoes, so that it catches the member 101 before the starting rod returns to its normal position.

In order to make clear the cycle of operations just described, with reference to the occurrence of the various operations during one complete revolution of the loom shaft, reference will now be had to the diagram of Fig. 14. The movement of the lay during one complete revolution of the loom shaft is graphically represented by the full line curve, the horizontal ordinates of the curve representing increments of time, and the vertical ordinates representing increments of movement of the lay between its extreme positions, so that the curve reaches each extreme position once during a complete revolution of the crank shaft. In considering the curve of Fig. 14, it is to be assumed that the loom has been operating normally up to the point A, when the filling feeler mechanism operates just before the lay reaches the center of its travel and the exhausted shuttle is picked from left to right. The starting rod 23 is therefore moved at the point A and sets in operation the several instrumentalities which bring about the results previously described, namely, the transfer latch 89 is held fast, a fresh bobbin is dropped in the magazine, the pawl 68 is lifted, and the plunger 97 is retracted. At B the shuttle, with practically exhausted filling, is picked to the right, and during the interval represented by C the box and harness motions cease to function as the pawl 68 has been lifted. At D the transerrer 22 is operated as the lay reaches the limit of its forward movement, thereby inserting a fresh bobbin in the shuttle. At E the picking mechanism is thrown off by the turning of the shaft 98, and during the interval represented by F the box and harness motions are resumed. At G the picking mechanism is again set in operation and the loom resumes normal operation.

From the foregoing then, it is apparent that by our invention we have provided a pick-and-pick loom employing multiple shifting boxes at each end thereof, and a magazine containing different kinds of filling from which any shuttle may be automatically replenished with the proper kind of filling. By our invention we have further provided a loom employing a magazine provided with compartments for a number of different kinds of filling equal to the number of shuttles employed in both sets of shifting shuttle boxes. By our invention then, we have provided a loom which is adapted to weave with as large a number of active shuttles as has ever been employed, any or all of these shuttles being adapted to be automatically replenished with filling of individual character, so that our loom does not have to be stopped on account of exhaustion of the filling in any active shuttle.

It is obvious that we may employ any suitable or usual form of warp stop motion in our loom, although many automatic filling replenishing looms have been operated without warp stop motions. In addition we can also apply to the transferring mechanism shown, any suitable or usual form of shuttle feeler, particularly as the latch member of the transferring mechanism shown, is held in operative position by spring means, and consequently a shuttle feeler could be employed to withdraw the latch. It is also obvious that we can employ suitable thread cutters cooperating with the loom temple and shuttle feeler, as shown and described in the co-pending application, George Crompton, Jr., Serial No. 629,890, filed April 4, 1923.

While we have chosen to illustrate our invention as being carried out by the use of certain specific devices, it is obvious that our invention is not limited to the use of such instrumentalities, but is susceptible of various modifications, and we desire therefore that only such limitations be imposed thereon as may come within the scope of the appended claims which are to be so construed as to cover all means of weaving with shuttles operated rightside up in shifting shuttle boxes or with cells cooperating with a filling replenishing mechanism of any desired type.

We claim,

1. In a loom, a lay provided with sets of shiftable shuttle boxes at opposite ends thereof, one set of boxes being movable on the lay in substantially the same direction that the lay moves, and automatic means to cause replenishment of filling in a shuttle in substantially a vertical plane in any one cell of the last named set of boxes.

2. In a pick-and-pick loom, a lay provided with sets of shifting shuttle boxes at op-

- posite ends thereof, movable in different directions, one set of boxes being movable on the lay in substantially the same arcuate path that the lay travels, and automatic 5 means to cause replenishment of filling in a shuttle in a substantially vertical plane in any one cell of the last named set of boxes.
3. In a loom, a lay carrying sets of shifting shuttle boxes at opposite ends thereof, 10 movable in planes substantially at right angles to each other, the plane of movement of one set of boxes being tangent to the arc of movement of the lay, and automatic means to cause replenishment of filling in 15 substantially a vertical plane in a shuttle in any one box of the last named set of boxes.
4. In a loom, a lay carrying sets of shifting shuttle boxes at opposite ends thereof, and weft replenishing mechanism cooperat- 20 ing with a set of boxes movable in a sub- substantially horizontal direction to cause a transfer in a direction substantially at right angles to the movement of the said boxes.
5. In a loom, a lay carrying sets of mov- 25 able shuttle boxes at opposite ends thereof, one set of said boxes being movable backwardly and forwardly and coincidently in an upwardly and downwardly direction, and weft replenishing mechanism cooperat- 30 ing with the latter set of boxes to cause a transfer in substantially a vertical plane.
6. In a loom, a lay carrying a set of sub- 35 stantially horizontally movable shuttle boxes, and weft replenishing mechanism co- operating with said shuttle boxes to bring about a transfer in a substantially vertical plane.
7. In a loom, a lay carrying a set of shift- 40 able shuttle boxes at one end thereof, a box shifting mechanism adapted to move said boxes on the lay in substantially a horizontal arcuate path, a filling magazine mounted above said lay adjacent said boxes and means for transferring fresh filling 45 carriers from said magazine to a shuttle in any one of said boxes while the lay is moving and the boxes are at rest, and means to cause the weft to be threaded in the running shuttle when the latter is picked from the transferring end of said lay.
8. In a loom, a lay carrying at one end a 50 set of shuttle boxes shiftable in a vertical plane and carrying at the other end a set of shuttle boxes shiftable in a substantially horizontal plane, and a weft replenishing mechanism cooperating with the horizontally movable boxes to bring about a transfer in a vertical plane.
9. In a loom, a lay carrying shifting shut- 60 tle boxes at each end thereof, one set of said boxes being movable in a substantially horizontal plane, and a filling changing mechanism cooperating with said horizontally movable set of boxes to effect a change of filling by movement in a vertical plane on

the practical exhaustion of the filling in any of said shuttles.

10. In a loom, a lay carrying shifting shuttle boxes at each end thereof, a gravity operated magazine adjacent the shuttle boxes at one end of said lay, and a transferer adapted by a vertical movement to insert a supply of filling from said magazine in a shuttle in any of the boxes below 75 said transferer.

11. In a loom, a lay carrying shifting shuttle boxes at each end thereof, means for raising or lowering the shuttle boxes at one end of said lay, means for moving the shuttle boxes at the other end of said lay back and forth on the lay, and filling changing mechanism cooperating with the last named set of boxes to cause a transfer in a vertical direction into any one cell. 80

12. In a loom, a lay carrying shifting shuttle boxes at each end thereof, a magazine above the shuttle boxes at one end of said lay, and operating means adapted by a vertical movement to insert a supply of filling from said magazine in a shuttle in any 90 of the boxes below said magazine.

13. In a loom, the combination with a lay carrying shifting shuttle boxes at each end thereof, mechanism for shifting one set of boxes on the lay in substantially the same 95 direction that the lay moves, a filling changing mechanism adjacent the shuttle boxes last named, and means for rendering the filling changing mechanism operative to effect a change of filling in substantially a vertical plane upon the practical exhaustion of the filling in any of the shuttles, of means for automatically interrupting the functioning of said box shifting mechanism prior to the accomplishment of a change of filling. 100

14. In a loom, the combination with a lay carrying shifting shuttle boxes at each end thereof, a filling magazine above the shuttle boxes at one end of the lay, means for vertically moving a filling carrier to any one of the boxes below the magazine and means for releasing a filling carrier in said magazine upon the practical exhaustion of filling in any of the shuttles, of a pattern controlled device cooperating with said magazine, whereby the filling on the released carrier is of the same character as the filling on the exhausted shuttle. 110

15. In a loom, a movable lay, shifting shuttle boxes at each end thereof and a stationary gravity operated weft replenishing magazine holding carriers of different character, filling indicator means, a separate auxiliary pattern chain cooperating with said filling indicator means for controlling the operation of said magazine, whereby the filling on the carrier released by said magazine is of the same character as the filling in the running shuttle which shuttle caused the indication. 115

16. In an automatic pick and pick loom a lay, a set of multiple celled shuttle boxes at each end thereof, at least one set of said boxes being of a non-gravity type operable into said boxes, said boxes having a slightly rising action as said lay moves forward, said action being imparted in part by said lay 10 and in part by said box motion.
- 5 in an arcuate path, a multiple colored magazine mounted above said boxes, means to transfer a filling carrier from said magazine
